UNITED STATES PATENT OFFICE.

CLAYTON SEYMOUR, OF BURLINGTON, VERMONT.

GAS-ENGINE TESTER.

1,239,974.

Specification of Letters Patent. Patented Sept. 11, 1917.

Application filed May 9, 1916. Serial No. 96,297.

To all whom it may concern:

Be it known that I, CLAYTON SEYMOUR, a citizen of the United States, residing at Burlington, in the county of Chittenden and State of Vermont, have invented certain new and useful Improvements in Gas-Engine Testers, of which the following is a specification.

My invention relates to improvements in automobile appliances, and relates particularly to a spark plug tester, whereby the operator or owner of an automobile or similar vehicle may always have at hand means for determining whether or not the spark plugs of the internal combustion engine are in proper condition.

An object of my invention is the provision of a spark plug tester which will tell at once whether the spark plug is working and the amount of spark which the plug is giving.

A further object of my invention is the provision of a spark plug tester which will be small in size; which will be cheap of production; and which will be durable and unbreakable.

With the above and other objects in view which will appear as the description proceeds, the invention consists in the novel construction, combination and arrangement of parts, hereinafter described and claimed, it being understood that changes in the precise embodiment of the invention herein disclosed can be made without departing from the spirit of the invention.

In the accompanying drawings I have illustrated one complete example of the physical embodiment of my invention constructed according to the best mode I have so far devised for the practical application of the principles of my invention.

Figure 1 is a front elevation of my invention showing its application, and

Fig. 2 is a central sectional view thereof.

Corresponding and like parts are referred to in the following description and indicated in all the views of the accompanying drawing by the same reference characters.

In the accompanying drawing, I have used the reference numeral 1 to indicate generally a spark plug which may be of the ordinary construction provided with ordinary screw threaded wire or rod at its outer end to receive a nut 2, the spark plug being secured in the cylinder 3.

My improvement comprises a body 4 made of fiber or other suitable insulating material

which may be readily molded. The body 4 is preferably yoke shape and is provided with a pair of depending arms 5, one of the arms 5 having at its end the terminal or contact point 6 having secured thereto the wire 6' which passes up through the arm to the sight opening 7 formed in the hand grasping portion 8 of the body 4, and the other arm has slidably mounted therein the contact pin 9 as will be hereinafter more clearly set forth.

The contact pin or stud 9 is mounted in the opening 10 in the longer of the arms 5, and has the spiral spring 11 to bear thereon so as to give the proper contact when in use. To prevent the pin 9 from becoming detached from the arm, I employ the stud 12 projecting into the opening 10 and engaging the slot 13 in the stud.

The spring 11 has its lower end soldered to the pin 9 and its upper end soldered to the wire 14 which is secured to the threaded bushing 15, in which is mounted the threaded adjusting screw 16, said adjusting screw 80 having its winged portion 16' made of rubber or other insulating material to prevent the operator from becoming shocked when adjusting it.

Carried by the end of the screw 16 is the 85 wire or rod 17 which passes through the bushing 15 into the sight chamber or opening 7.

As will readily be seen in Fig. 1, the contact point 6 is placed against the nut 2 of 90 the spark plug and the contact pin 9 is placed upon any part of the cylinder, the tension of the spring 11 causing it to make a perfect contact, and that the current passes through the wires 6' and 17 by means of the 95 contact point 6 and the contact pin 9.

After placing the device as stated above, the screw 16 is adjusted until the spark gap 18 formed by the ends of the wires 6' and 17 is about $\frac{1}{2}$ of an inch in size, and if the 100 spark plug is working a spark will be readily apparent through the sight opening 7.

By my device it is seen whether the spark plug is working and if so the strength of the spark as will be readily understood by 105 all who are skilled in the art to which this invention appertains.

Thus it will be understood that I provide a device which will be small and compact in size so that it can be readily carried in the 110 tool box; one that will be capable of ready application so as to ascertain which spark

plug is working and the amount of spark which each plug is giving; and one which will be cheap of construction, and practical and durable from every stand point.

5 I claim:—

A spark plug tester, consisting of a yoke forming a hand grasping portion and a pair of arms, a visible spark gap or sight opening in said hand grasping portion, contact points in each of said arms, one of said contact points being rigid and the other slidably mounted, a spiral spring bearing against said slidable contact point, a steel bushing

in one end of said hand grasping portion, a wire connecting said spring and bushing, an 15 adjustable screw mounted in said bushing, and a wire carried by said screw whereby the space between the end of the said wire and the wire leading from said rigid contact point may be adjusted.

20 In testimony whereof I affix my signature in the presence of two witnesses.

CLAYTON SEYMOUR.
